UNITED STATES PATENT OFFICE.

JACOB VAN ECK, OF MIDDDELBURG, NETHERLANDS.

OPEN-END WRENCH OF THE ADJUSTABLE-JAW TYPE.

Application filed June 12, 1926, Serial No. 115,617, and in Germany September 22, 1925.

My present invention relates to open end wrenches of the type in which one jaw is hinged to the handle, the other jaw being slidably mounted relative to the hinged jaw and connected with the handle through a rod of adjustable length. The object of my invention is to generally improve the construction of known wrenches of this type and to provide an open end wrench which is easy to handle. With these objects in view, I suggest to mount the jaws in an inclined position relative to the axis of the handle so that the hinged jaw is nearer to the free end of the handle than is the slideable jaw and also its hinge is nearer to said free end than is the connection between the slideable jaw and the adjustable rod, and further, to provide the handle on both side faces and on either side of the hinge with abutments for the hinged jaw, the said rod being adapted to perform a swinging movement in the space between said abutments.

In order that my invention may be fully understood, I shall proceed to describe the same with reference to the annexed drawing, on which:

Fig. 1 shows a side elevational view of a screw wrench,

Fig. 2 a sectional elevation of said wrench and

Fig. 3 a cross sectional view along the line III—III in Fig. 1.

Fig. 4 shows a side elevational view of a pipe wrench.

The jaw 2 of the screw wrench according to Figs. 1—3 is hinged as at 3 to the handle 1. Said jaw is provided with a rectilinear guideway for the jaw 4, which is pivoted as at 5 to a rod 6 threaded on its lower end portion so that its operative length can be adjusted by means of a nut 7 located between two filling pieces 8, 9. A spring blade 10, riveted as at 11 to the handle 1 and exerting a certain amount of pressure as at 12 against the rod 6, tends to hold the jaw 2 in engagement with abutments 13 on the side faces of the handle. Similar abutments 14 serve to take up the pressure of the hinged jaw 2 when the screw wrench is used in a reversed position (as compared with the position for normal use) for tightening up or loosening nuts which are not easily accessible.

The screw wrench is shown in a position in which it is used for tightening up a nut

on a right hand threaded screw bolt, said nut being shown in dash and dot lines. By means of the nut 7, the wrench is first adjusted to fit the nut to be tightened up. If, then, the handle 1 is forced to the left, it tends to swing about the pivots 3 of the jaw 2, whereby a pull is exerted through the rod 6 on the jaw 4, so that the nut is clamped between the jaws, the clamping force being proportionate to the resistance offered by the nut against its rotation.

If the handle has moved through a sufficient angular distance, it is moved back (i. e. to the right), when it again swings about the pivots 3. The rod 6 now acts as a push rod against the jaw 4 so as to move the same away from the jaw 2, whereby the nut to be tightened up is released and the jaws turn through a small angular distance in an anticlockwise direction. At first, however, said angular distance is insufficient to permit the jaws to pass the corners of the nut, so that the swinging movement of the handle 1 about the pivots 3 is continued and the jaw 4 moves further away from jaw 2, equal to the maximum diameter of the nut. When the distance between the jaws is equal to the maximum diameter of the nut, the jaws pass the corners of the nut and are restored to their normal positions by the action of spring 10 so as to grip the next pair of parallel nut faces, and so on.

If the nut is to be loosened, the wrench is used in the reversed position.

Fig. 4 does not require to be explained in further detail, since the pipe wrench illustrated therein corresponds in construction with that of the above described screw wrench.

What I claim is:—

1. An open end wrench including a jaw hinged to the handle, another jaw slidably mounted relative to the hinged jaw and an adjustable rod connected with the slideable jaw and the handle, said jaws being mounted in an inclined position relative to the axis of the handle so that the hinged jaw is nearer to the free end of the handle than is the slideable jaw and also its hinge is nearer to said free end than is the connection between the slideable jaw and the adjustable rod, and further characterized by the fact, that the handle is provided on both side faces and on either side of the hinge with abutments for the hinged jaw, the said

rod being adapted to perform a swinging movement in the space between said abutments.

2. An open end wrench including a handle, a jaw member pivoted to the handle, abutment means on the handle to engage with the jaw upon relative movement between the jaw and the handle, a slidable jaw mounted in the jaw which is pivoted to the handle, means for setting the slidable jaw with reference to the pivoted jaw, and means for yieldingly placing said last named means under tension.

3. An open end wrench comprising a

handle, a jaw pivoted to the handle, abutment means on the handle at opposite sides of the pivot and adapted to engage the jaw upon relative movement between the same and the handle, a jaw slidably mounted in the pivoted jaw, a member having one end pivotally connected to the slidable jaw, means for engaging the other end of said member to adjust the same longitudinally and also permit of its swinging movement, and a spring for tensioning the swinging movement of said member.

In testimony whereof I affix my signature.
JACOB VAN ECK.
